UNITED STATES PATENT OFFICE

ROSE B. QUINE, OF NEWTON, MASSACHUSETTS

APPAREL GARMENT

Application filed April 5, 1932. Serial No. 603,407.

This invention relates to an apparel garment which may be of any suitable corset type, and includes a body-embracing band composed of inelastic sections having opposed front and back edges located respectively at the median line of the front and back of the body when the garment is in use, and having fasteners nonadjustably connecting the front edges, and a lacing adjustably connecting the rear edges, the garment including also abdomen supporting means within said band.

One object of the invention is to provide a garment which includes a body-embracing band thus characterized, and improved abdomen-supporting means within the band organized to exert pressure across the abdomen when the front and rear edges of the band are connected by said fasteners and lacing, said pressure being maintained by the fasteners and lacing of the embracing band and variable by adjustments of said lacing, the improved garment being adapted to overcome certain troubles, including those known as sagging muscles and dropped stomach.

Another object is to provide a garment which includes said body-embracing band and means associated therewith for exerting a supporting pressure on the sacro-iliac region of the wearer's body.

Of the accompanying drawings forming a part of this specification,—

Figure 1 is a side view of a garment embodying my invention showing its inner side, the garment being opened.

Figure 2 is a sectional view showing the garment partially closed.

Figures 3 and 4 are fragmental sectional views illustrating the function of the sacro-iliac supporter hereinafter described.

Figure 5 is a front view showing the abdominal supporting means closed on the body, the sections of the body-embracing band being opened.

Figure 6 is a section on line 6—6 of Figure 5.

Figure 7 is a front view, and 8 a rear view, each showing the garment closed.

The same reference characters indicate the same parts in all of the figures.

The sections 12 and 13 of the body-embracing band may be of any suitable form and construction, and have separable fasteners designated by 14 and 15 non-adjustably connecting their front ends, and a lacing 16 adjustably connecting their rear ends.

Within the body-embracing band is an abdominal supporter composed of two wings including elastic inner members 17 whose inner ends are attached at 19 to the mid length 60 portions of the sections 12 and 13, and free flexible inelastic outer members 20 and 21 having meeting ends provided with separable fasteners 22 and 23 non-adjustably connecting said ends. Said end members are 65 each preferably composed of two layers of suitable cloth stitched together. The outer end member 20 is longer than the end member 21, and the wings are so arranged that the longer end member 20 extends across the vertical center of the abdomen and covers an extended lower portion of the latter at opposite sides of said center, as best shown by Figure 5.

Each of the elastic inner members 17 is 75 preferably composed of parallel strips of elastic webbing. Said inner members are normally contracted and are tensioned when the garment is being donned and when the wings are connected with each other by the fasteners 22 and 23, so that said wings exert pressure across the abdomen, the longer outer member 20 being pressed against the central portion of the abdomen.

The garment is adapted to be conformed to the body in abdominal supporting relation thereto by first connecting the wing members 20 and 21 with each other by the fasteners 14 and 15, while the rear lacing 16 is relatively loose, then connecting the front ends of the sections 12 and 13 with each other by the fasteners 14 and 15, and finally taking up the looseness of the rear lacing. Said lacing is elongated so that it has end portions adapted to be tied together at the front of the garment, the lacing being preferably endless, portions of it being disposed in a pair of loops 16a (Figure 1), adapted to be tied together. Two pairs of said loops may 100 be provided if desired.

The longer end member 20 is preferably "boned" by providing it with resilient stiffening strips 25, which may be whalebone or any suitable substitute therefor, the strips being interposed between the cloth layers of said member, and arranged to extend from the lower to the upper edge thereof. Said strips impart a resilient flexibility to the end member 20, and enable it to effectively support the abdomen in the manner described.

To increase the efficiency of the abdominal supporter in preventing the downward sagging of the lower portion of the abdomen causing what is known as dropped stomach, I may provide the lower edges of said wings, including the elastic members 17 and the end members 20 and 21, with an inelastic binding 250, adapted to cause the entire lower edges of the wings to positively or inelastically confine the lower portion of the abdomen and prevent downward sagging thereof. The elasticity of the major portions of the elastic members 17 is not affected by said bindings, so that said portions permit the larger end member 20 to conform yieldingly to the central portion of the abdomen above the positively confined portion as indicated by Figure 6.

A compressible pad shown by Figures 1 and 2, for treatment of hernia and other troubles, may be sewed or otherwise detachably secured to the longer end member 20. Said pad is here shown as composed of two sections 26 and 27 arranged to bear on the abdomen at opposite sides of the vertical center thereof. Either of said sections may be used without the other, as occasion may require, so that the pad may bear on the abdomen only at one side, or on both sides, of the vertical center thereof. A single pad equal in area to the two sections here shown may be employed if desired.

The larger end member 20 may be provided with two depending stocking supporters, each composed of a strap 28 attached to the lower end of said member, at opposite sides of its vertical median line and a stocking leg gripping member 29 on the lower end of the strap. The supporters are so arranged that one is engageable with a "right" and the other with a "left" stocking leg, the object being to prevent upward creeping or displacement of the abdominal supporter.

The garment may include with the sacro-iliac supporter next described.

Attached at 30 to the sections 12 and 13 adjacent the rear ends thereof are two elastic tabs 31, of flexible material and preferably of elastic goring fabric. Said tabs are secured at their forward ends to the intermediate portions of the band sections and have free ends extending toward the rear ends of said sections, as shown by Figures 1 and 2.

Said tabs are within the outer band and

are formed and arranged to bear on portions of the sacro-iliac region.

Movable on the external surfaces of the outer band sections are two pull straps 33, one having a buckle 35 whereby it may be adjustably connected with the other. 70

Flexible tapes 34 extending loosely through eyelets 36 in the free ends of the tabs 31 and through eyelets in the rear ends of the outer band sections, are attached to the inner extremities of the belt ends 33. 75

The arrangement is such that opposite end-wise movements of the pull straps in the directions indicated by the arrows α — α stretch and tension the elastic tabs 31, and cause them to exert pressure on the sacro-iliac region, said pressure being releasably maintained by the engagement of the buckle 35 on one strap with the other strap. 80

The pull straps 33, arranged as shown, constitute a suitable embodiment of means for pulling the tapes in the directions required to tension the tabs and cause supporting pressure thereof on the sacro-iliac region. The buckle 35 constitutes a suitable embodiment of means for releasably maintaining said pressure. Any other suitable tape pulling means and pressure maintaining means may be employed. 85

The body-embracing garment may include the sacro-iliac supporter without the abdominal supporter, or with other abdominal supporting means. 95

I claim:

1. An apparel garment comprising a sectional back laced body-embracing band, and a sacro-iliac supporter including flexible tabs having fixed ends attached to the intermediate portion of the band sections, and free ends extending toward said rear edges, said tabs being within the band and formed and arranged to bear on the sacro-iliac region, flexible tapes engaged with the free ends of said tabs and extending therefrom through eyelets in the rear portions of the band sections to the exterior of the band, means for pulling said tapes in directions required to tension the tabs and cause supporting pressure thereof on the sacro-iliac region, and means for releasably maintaining said pressure. 100

2. An apparel garment comprising a sectional back laced body-embracing band, and a sacro-iliac supporter including flexible tabs having fixed ends attached to the intermediate portions of the band sections, and free ends extending toward said rear edges, said tabs being within the band and formed and arranged to bear on the sacro-iliac region, flexible tapes engaged with the free ends of said tabs and extending therefrom through eyelets in the rear portions of the band sections to the exterior of the band, pull straps located outside the band and connected with the outer ends of said tapes and movable to 110

120

125

130

pull the tapes in directions required to tension the tabs and cause supporting pressure thereof on the sacro-iliac region, and means for releasably confining said straps to maintain said pressure.

- 5 3. An apparel garment comprising a sectional back laced body-embracing band, and a sacro-iliac supporter including flexible tabs having fixed ends attached to the intermediate portion of the band sections, and free ends extending toward said rear edges, said tabs being within the band and formed and arranged to bear on the sacro-iliac region, flexible tapes engaged with eyelets in the free
10 ends of said tabs and extending therefrom through eyelets in the rear portions of the band sections, and a pair of belt ends movable on the external surface of the band, and attached to the outer ends of said tapes, the
15 arrangement being such that opposite endwise movements of said belt ends stretch and tension said tabs and cause them to exert supporting pressure on the sacro-iliac region, the belt ends having means whereby they
20 may be separably and adjustably attached to
25 each other to maintain said pressure.

In testimony whereof I have affixed my signature.

ROSE B. QUINE.
